UNITED STATES PATENT OFFICE.

EDWARD B. WESTON, OF DAYTON, OHIO.

DISPLAY-RACK ATTACHMENT.

No. 900,332.

Specification of Letters Patent.

Patented Oct. 6, 1908.

Application filed August 19, 1907. Serial No. 389,196.

To all whom it may concern:

Be it known that I, EDWARD B. WESTON, a citizen of the United States, residing in Dayton, county of Montgomery, and State of Ohio, have invented certain new and useful Improvements in Display - Rack Attachments, of which the following is a full, clear, and exact description, reference being had to the accompanying drawings, forming part of 10 this specification.

My invention relates to attachments to be applied to racks, or shelves, upon which goods are displayed for the purpose of permitting the boxes or packages containing the 15 goods to be drawn out, but held at the edge of the shelf, so that the lid or cover can be raised to remove the contents of the package without the necessity of removing the package entirely from the display shelf.

20 The special purpose of my invention is to provide such attachments for use with cans or boxes, in which the lid is hinged to the can at the back, and in which the attachments can be readily and easily applied to the 25 shelves and connected with the can, so that upon drawing out the can from the shelf, the lid may be opened and remain open to permit the ready removal of the contents of the can while the can is held at the edge of the 30 shelf.

It has been customary in the construction of attachments for this purpose to connect the attachments to the lid of the can, so that in supporting the can to the edge of the shelf 35 when pulled out, the strain of the weight of the can and contents has been applied to the hinge of the lid and as a result these hinges are frequently ruptured or broken away, and it is the special purpose of my invention to 40 provide a construction in which the strain of the attachment is removed entirely from the lid, and the entire attachment is secured between the body of the can and the shelf.

45 A further purpose of the invention is to supply an attachment which can be readily secured in place on the display shelves without requiring any accurate adjustment, so that any one no matter how unskilled can apply the attachment, it being understood 50 that the attachment is intended to be applied to shelves already in use in stores and the like, as well as for shelves as they are shipped from the factory.

55 In the drawings Figure 1 is a perspective view of my improved attachment removed from the can and shelf. Fig. 2 is a vertical

cross section of the can with the attachment applied thereto. Fig. 3 is a side elevation of a portion of the display rack showing the attachment applied to the can with the can 60 drawn out for removal of the contents, but before throwing up the lid.

1 is a part of a side standard, and 2—2 are sections of two of the shelves of any construction of display rack, and 3 is the can 65 such as is used ordinarily for the display of cracker goods, cakes and the like. These cans are usually made with an inner flange 4 around the upper and inner edge of the body of the can, and they are usually provided 70 with a flanged lid 5 hinged at the rear at 6 to the body of the can.

The holder for the can comprises a rod 7 slightly longer than the width of the can, with its ends 8 bent at right angles, and provided with the spring clips 9—9 at each end. 75 These clips are shaped to curve over the upper edge of the can body, and to be secured in place by engagement under the rim 4.

10 and 11 are connecting bars hinged at 80 12, so that these bars will fold together, and the outer end of the bar 10 is loosely strung or mounted on the rod 7, so that it will rotate thereon, and also slide laterally. The outer end of the bar 11 is given a right angle turn 85 at 17, and is bent over at 13 to form a right angle flange, which is pivoted at 14 to the clip 15, provided with openings 16, by which the clip can be secured to the rear edge of the shelf as shown in Fig. 3 by screws or nails. 90

In order to attach the device, the lid of the can is thrown open, the rod 7 placed across the back of the can underneath the hinge 6, and the spring clips 8 caught over the flange 4, as shown in Fig. 2. The connecting bars 95 10—11 are then slid on the rod 7 to about the middle position, and the clip 15 is nailed or screwed to the rear edge of the shelf immediately above the can. The hinged connecting bars 10—11 are mounted in a vertical plane 100 on the rod 7, and the outer end of the bar 11 is turned at right angles so as to fit against the rear edge of the shelf as the can is drawn out, thus keeping the cans in perfect alignment when pulling them forward, or replacing them in the rack, and thus the cans are prevented from working sidewise. In addition to this when the can is replaced, the bars 10—11 fold downwards, and serve as a back stop for the cans, maintaining a perfect alignment for the cans in front. 105

Having thus described my invention, what

I claim as new, and desire to secure by Letters Patent is:—

1. In a display rack attachment, the combination with the shelves of the rack, of a rod 5 extending across the rear of the can underneath the hinge of the lid, and spring clips for securing said rod to the body of the can, with a folding lever comprising a plurality of bars pivoted together, one end of one of said 10 bars being mounted on said rod to slide laterally, and the other end permanently secured to the back edge of the shelf above the can.
2. In a display rack attachment, the combination with the shelves of the rack, of a rod 15 extending across the rear of the can under-

neath the hinge of the lid, and spring clips for securing said rod to the body of the can, with a folding lever comprising a plurality of bars pivoted together in a vertical plane, with one end of one of said bars mounted on 20 said rod to slide laterally, and with the outer end of the other of said bars bent at right angles to the body of the bar, and a clip pivoted thereto, with means for securing the clip to the rear edge of the shelf above the can.

EDWARD B. WESTON.
